UNITED STATES PATENT OFFICE.

JOHN B. WHITACRE, OF CANTON, OHIO.

LUBRICATOR.

SPECIFICATION forming part of Letters Patent No. 296,493, dated April 8, 1884.

Application filed October 22, 1883. (No model.)

To all whom it may concern:

Be it known that I, JOHN B. WHITACRE, a citizen of the United States, and a resident of Canton, Ohio, have invented certain Improvements in Lubricators, of which the following is a specification.

My invention relates to an improvement in that class of lubricators in which the oil under pressure is caused to pass through a contracted opening, and is fed into a steam pipe or chamber containing steam, the object of my invention being to construct a simple and direct-acting lubricator of this character.

In the accompanying drawings, Figure 1 is a diagram, showing one method of using my improved lubricator; and Fig. 2, a sectional view on a larger scale of the lubricator.

A is a steam-pipe having a branch, *a*, from which projects an elbow-pipe, *b*, the lower end of the latter being connected to the lower end 20 of a casing, *B*, containing oil. This casing *B* has at the top a nozzle, *d*, tapered for the reception of a needle-pointed valve, *D*, the threaded stem of which is adapted to a threaded 25 opening in the lower portion of the casing, and is furnished outside of the same with a suitable operating-handle. The lower end of a tube, *F*, preferably of glass, is secured to the top of the casing *B*, and surrounds the nozzle *d*, the upper end of said tube being secured 30 to the casing *G* of a valve in the branch pipe *a*.

When the apparatus is in operation, the elbow-pipe *b* and tube *F* are filled with water of condensation, the weight of the water in 35 said pipe *b* exerting an upward pressure on the oil in the reservoir *B*, and causing the same to escape from the nozzle *d*, the escaping oil rising through the water in the tube *F* and entering the branch *a*, through which it finds 40 its way to the steam in the pipe *A*. The rate of flow of oil through the nozzle *d* is regulated

by the adjustment of the valve *D*, this being effected by simply turning the handle with which the valve-stem is provided.

The reservoir *B* is filled with oil through a 45 neck, *f*, provided with a suitable stopper, and the water of condensation is drawn off from the reservoir at intervals through a cock, *h*.

Instead of connecting the reservoir to an elbow-pipe, *b*, as shown, said reservoir may be 50 connected directly to the boiler at a point below the water-line, so as to insure the necessary head of water for feeding the oil.

The advantages of my invention are its simplicity of construction and cheapness of manufacture as compared with other devices of the 55 same class.

The nozzle *d*, being in the top of the casing, provides for a free and direct flow of the oil from the reservoir, and permits the discharge 60 of all of the oil contained therein.

I claim as my invention—

1. The combination of the reservoir *B*, having in the top a nozzle, *d*, with the needle-pointed valve *D*, adapted to the nozzle, and 65 having a threaded stem adapted to a threaded opening in the bottom of the reservoir, as set forth.

2. The combination of the reservoir *B*, having a nozzle, *d*, the needle-pointed valve *D*, 70 adapted thereto, and to a threaded opening in the reservoir, and the tube *F*, secured to the reservoir and surrounding the upper end of the nozzle, as set forth.

In testimony whereof I have signed my name 75 to this specification in the presence of two subscribing witnesses.

JOHN B. WHITACRE.
